FIGURE 1 is a perspective view of a ladder showing a first embodiment of my new design;

FIGURE 2 is an enlarged, fragmentary perspective view of a rung end portion of the ladder of FIGURE 1 as viewed generally from the inside of a side rail thereof;

FIGURE 3 is an enlarged, fragmentary perspective view of the rung end portion of the ladder of FIGURE 1 as viewed generally from the outside of a side rail thereof;

FIGURE 4 is a perspective view of a ladder showing a second embodiment of my new design;

FIGURE 5 is an enlarged, fragmentary perspective view of a rung end portion of the ladder of FIGURE 4 as viewed generally from the inside of a side rail thereof;

FIGURE 6 is an enlarged, fragmentary perspective view of the rung end portion of the ladder of FIGURE 4 as viewed generally from the outside of a side rail thereof;

FIGURE 7 is a perspective view of a ladder showing a third embodiment of my new design;

FIGURE 8 is an enlarged, fragmentary perspective view of a rung end portion of the ladder of FIGURE 7 as viewed generally from the inside of a side rail thereof;

FIGURE 9 is an enlarged, fragmentary perspective view of the rung end portion of the ladder of FIGURE 7 as viewed generally from the outside of a side rail thereof;

FIGURE 10 is a perspective view of a ladder showing a fourth embodiment of my new design;

FIGURE 11 is an enlarged, fragmentary perspective view of a rung end portion of the ladder of FIGURE 10 as viewed generally from the inside of a side rail thereof; and

FIGURE 12 is an enlarged, fragmentary perspective view of the rung end portion of the ladder of FIGURE 10 as viewed generally from the outside of a side rail thereof.

The dominant features of my design reside in those portions shown in full lines on the drawing.

This is a continuation-in-part application of pending applications Ser. Nos. 87,990, 87,991, 87,992 and 87,993, all of said applications filed Nov. 3, 1965, and all of said applications are now abandoned.

I claim:

The ornamental design for a ladder, as shown and described.
